DESIGN FOR A MOLDED BOTTLE
CARRYING CASE

Harper Richards, Chicago, Ill., assignor to The Richardson Company, Lockland, Ohio, a corporation of Ohio

Application September 16, 1946, Serial No. 133,347

Term of patent 7 years

(Cl. D58—13)

To all whom it may concern:

Be it known that I, Harper Richards, a citizen of the United States, residing at Chicago, in the county of Cook and State of Illinois, have invented a new, original, and ornamental Design for a Molded Bottle Carrying Case, of which the following is a full, clear and exact description, reference being had to the accompanying drawings, forming a part thereof.

In the drawings:

Fig. 1 is a top perspective view of a molded bottle carrying case, showing my new design,

Fig. 2 is a top plan view thereof,

Fig. 3 is a side elevational view thereof, and
Fig. 4 is an end elevational view thereof.

I claim:

The ornamental design for a molded bottle carrying case, substantially as shown.

HARPER RICHARDS.
